CLAIM

The ornamental design for a computer console end, as shown and described.

DESCRIPTION

FIG. 1 is a perspective view of a computer console end showing our new design;

FIG. 2 is a front elevational view thereof;

FIG. 3 is a rear elevational view thereof;

FIG. 4 is a top view thereof;

FIG. 5 is a left side elevational view thereof; and,

FIG. 6 is a right side elevational view thereof.

The broken line representations of portions of a computer console shown in FIGS. 1-4 and 6 are shown for illustrative purposes only and form no part of the claimed design.
